ATTORNEYS.

UNITED STATES PATENT OFFICE.

ELIJAH THOMAS GASKILL, OF NEWBERN, NORTH CAROLINA.

SASH-HOLDER.

No. 904,419.

Specification of Letters Patent.

Patented Nov. 17, 1908.

Application filed July 3, 1908. Serial No. 441,774.

To all whom it may concern:

Be it known that I, ELIJAH THOMAS GASKILL, a citizen of the United States, and a resident of Newbern, in the county of Craven and State of North Carolina, have invented certain new and useful Improvements in Sash-Holders, of which the following is a specification.

This invention is an improvement in sash holders; and consists in certain novel constructions and combinations of parts as will be hereinafter described and claimed.

In the drawings—Figure 1 is a face view of a window embodying my invention. Fig. 2 is a detail vertical section of a portion thereof. Fig. 3 is a cross section on about line 3—3 of Fig. 2, and Fig. 4 illustrates in side and edge view a retaining device having two rollers instead of one as shown in Fig. 2.

By my invention I seek to provide a sash that can be moved up and down with equal facility and will be retained in any position to which it may be adjusted.

In carrying out my invention I provide one of the window strips, which may be the parting bead or the other strip as desired, but it is usually the inner strip of the window, with a corrugation A, extending vertically and providing a series of depressions in which a spring actuated roller carried by the sash may operate, the roller being forced past the elevations of the corrugation in adjusting the window up or down and seating in the depression to hold the sash in any desired adjustment.

In the construction shown the roller B is mounted eccentrically on the shaft C, which latter is journaled in a spring actuated support so that the roller rotates on the axle or shaft, and the said axle or shaft also rotates this being important in preventing jamming in the operation of the invention. The spring actuated support is shown as a plate spring D, having lugs D', at its middle point providing a bearing for the axle C, and said plate spring D is bowed outwardly between its ends and is yieldingly secured at its end D² to its carrier or base plate E by means of a pin F extending through a longitudinal slot F' in the plate D, the other end of the plate being usually fixed to the plate E by a rivet as shown, or in any other suitable manner.

The carrier or base plate E has its ends E' deflected forming spurs which may be

driven into the wood of the window sash in securing the device in position for use.

In operation it is preferred to recess the window sash at G to receive the device for actuating the roller and to steady the said device in position when applied as best shown in Fig. 2 of the drawing. Usually I provide each sash with roller devices arranged at the corners of the sash as will be understood from dotted lines Fig. 1.

The rollers may be duplicated and two or more used in each device according to the weight or size of the sash, two rollers being shown as mounted on the spring plate in Fig. 4 of the drawings.

It will be noticed that in operation the sash will be held from rattling and can be secured in any desired position up or down and will be dust proof from the outside in the use of the invention.

The corrugated window strip it will be noticed forms a seat for the spring actuated roller and when two or more rollers are provided, as will be understood from Fig. 4, they are so spaced apart as to operate in their respective depressions in the said corrugated seat.

The corrugations are preferably of the ratchet form as shown, this construction permitting the sash to be raised readily and yet aiding in holding the sash in any desired adjustment and in permitting the same to be forcibly pulled down when desired, the shoulder of the ratchet being arranged to face upwardly as illustrated in Figs. 2 and 4 of the drawing.

I claim—

1. The combination substantially as herein described of a window sash having a recess in its face, a base plate or carrier fitted in said recess and provided at its ends with spurs driven into the sash, a plate spring bowed outwardly between its ends and secured at one end to the base plate of the carrier and slidable at its other end relatively to the base plate or carrier, the said spring plate having between its ends outwardly projecting lugs or ears, an axle or shaft journaled loosely in said ears, a roller eccentrically on the axle or shaft between the said lugs, and a corrugated seat against which the said roller bears, substantially as set forth.

2. The combination with a window sash and its frame, of a spring on one of said parts a roller journaled eccentrically and

carried by the spring on one of said parts, and a corrugated strip carried by the other part and forming a seat for said roller, substantially as set forth.

5 3. A window retaining device comprising a base plate or carrier, a spring plate held thereto and bowed outwardly between its ends, and an eccentrically journaled roller carried by said spring.

10 4. The improvement herein described com-

prising a carrier, a plate spring held to and slideable relatively to the carrier and having an outwardly bowed portion between its ends, and lugs or ears projecting therefrom, and a roller journaled between said lugs or 15 ears, substantially as set forth.

ELIJAH THOMAS GASKILL.
